UNITED STATES PATENT OFFICE.

STEVE RICKEY, OF MOOSEHORN, MANITOBA, CANADA, ASSIGNOR OF ONE-HALF TO
STEVE CHORNY, OF MOOSEHORN, MANITOBA, CANADA.

VELOCIPEDE.

1,427,417.

Specification of Letters Patent. Patented Aug. 29, 1922.

Application filed September 15, 1921. Serial No. 500,731.

To all whom it may concern:

Be it known that I, STEVE RICKEY, a citizen of the Dominion of Canada, residing at Moosehorn, in the Province of Manitoba and 5 Dominion of Canada, have invented certain new and useful Improvements in Velocipedes, of which the following is a specification.

This invention relates to certain new and 10 useful improvements in velocipedes which may be conveniently employed as a baby carriage so that the attendant of an infant may manually propel the carriage from place to place.

15 The primary object of the invention is to provide a device of the above character which embodies such construction as to enable ready steering and propulsion and including a body or receptacle for an infant 20 disposed forwardly of the attendant so that he or she may give the required attention to the infant when necessary.

Another object of the invention is to provide a simplified and durable construction 25 of manually propelled baby carriage.

Other objects will appear as the nature of the invention is better understood and the same consists in the novel form, combination and arrangement of parts hereinafter 30 more fully described and shown in the accompanying drawings, in which like reference characters indicate corresponding parts throughout the several views.

In the drawings,

35 Figure 1 is a side elevational view of a velocipede baby carriage constructed in accordance with the present invention,

Figure 2 is a top plan view thereof,

Figure 3 is a horizontal sectional view 40 drawn on a larger scale and taken substantially upon line III—III of Figure 1,

Figure 4 is a transverse sectional view taken upon line IV—IV of Figure 3,

Figure 5 is an enlarged horizontal sectional view taken upon line V—V of Figure 1 and partly broken away.

Figure 6 is a fragmentary elevational view drawn on a larger scale and showing the supporting connection between the steering 50 post and the rear end of the body, and

Figure 7 is a horizontal sectional view taken upon line VII—VII of Figure 6.

Referring more in detail to the several views, the present invention embodies a body 55 or receptacle 5 which may be of any usual or

preferred form for accommodating an infant or child having its forward end yieldingly supported at a suitable elevation above the forward end of a horizontal frame bar 6 by means of flexibly connected spring elements 7 and 8 which are preferably of sheet or leaf form and which are respectively swiveled to the bottom of the body 5 and to the end portions of a transverse front axle 9. The axle 9 has supporting wheels 10 60 suitably journaled upon the ends thereof and is centrally slotted as at 11, the forward end of the frame bar 6 being projected into the slot 11 and there pivoted to the axle by means of a pin 12 so that the axle may be 65 swung for steering the device.

A post 13 is rigid with and projects substantially vertically and upwardly from the frame bar 6 between the ends of the latter and the same is spaced from said bar 6 at 70 opposite sides by means of suitable braces 14, the post 13 being hollow and having an annular flange 15 upon its upper end. A steering post 16 with handle bars 17 is journaled in the post 13 and has a collar 18 75 fixed thereon which bears upon the flange 15 so as to hold the steering post at the required elevation. The collar 18 has a pair of oppositely extending transverse arms 19 rigid therewith and the outer ends of these arms 80 are pivotally connected as at 20 with the adjacent ends of rearwardly converging connecting rods 21 which have their forward ends loosely and pivotally connected as at 22 to the opposite end portions of the axle 90 9 between the spring members 8 and the supporting wheels 10. Thus, when the steering post 16 is rotated, swinging of the axle 9 is effected for steering.

The body 5 has a forked bracket 23 rigidly fastened to the rear end of the same, and the fork of this bracket embraces the steering post 16 above the collar 18 and rests upon an annular enlargement 24 of said steering post 16 so that the rear end of the 100 body is supported at the desired elevation without preventing rotation of the steering post, said bracket 23 being held into engagement with the steering post by means of a relatively strong spring 25 or the like 105 which is attached to the body beneath the bracket 23 and also to the tubular post 13 beneath the flange 15 of the latter. Springs 26 are preferably connected between the axle 9 and the horizontal frame bar 6 at oppo- 110

site sides of the pivot 12 for normally maintaining the axle at right angles to the frame bar 6 for maintaining a straight course to the device unless manually changed by operation of the steering post.

A pair of converging rigidly connected bars 27 extend upwardly from the horizontal frame bar 6 and are rigid with the latter rearwardly of the steering post in a position to support a suitable seat 28 for the operator, the rear bar 27 being in the form of a fork with a rear supporting wheel 29 journaled therein. A sprocket wheel 30 is associated with the wheel 29, while a second sprocket wheel 31 is fixed upon a crank shaft 32 journaled transversely in the horizontal frame bar 6 at the bottom of the upright post 13, and a chain 33 passes around these sprocket wheels. The crank shaft 32 is provided with the usual operating pedals 34, and as the sprocket wheel 30 is in fixed relation with the rear supporting wheel 29, rotation of the crank shaft 32 will be imparted to said supporting wheel through the sprocket wheels and chain described.

In operation, the operator is seated upon the seat 28 with his feet resting upon the pedals 34 and the handles 17 grasped in a well known manner. By operating the pedals 34, forward propulsion of the vehicle will be had as above described and steering of the vehicle may be accomplished by simply turning the steering post and causing one of the arms 19 to exert a pull upon the connecting rod 21 pivoted thereto while the other arm causes a forward movement of the other connecting rod 21 thereby swinging the axle 9 about the pivot 12 against the action of the springs 26.

It will be seen that the present invention embodies a simple and desirable form of manually propelled baby carriage which may be utilized for taking children from place to place without undue fatigue to the attendant.

Minor changes may be made without departing from the spirit and scope of the invention as claimed.

What is claimed as new is:

A device of the class described comprising a horizontal frame bar with a transverse steering axle centrally pivoted to the forward end thereof upon a vertical axis, a hollow post extending upwardly from said horizontal bar and rigid with the latter substantially midway between the ends of the same, a steering post journaled in said upright tubular post, a body, flexible means between the axle and the body for resiliently supporting the forward end of the latter at a desired elevation above the horizontal frame bar, means interposed between the steering post and the rear end of the body for supporting said rear end of the body at the desired elevation and for permitting free rotation of the steering post, means connecting said steering post with the opposite end portions of the axle for effecting swinging movement of the latter upon rotation of said steering post, a seat, means supporting said seat above the horizontal frame bar rearwardly of the steering post, a supporting wheel situated in the plane of the longitudinal axis of the body and journaled at the rear end of said horizontal frame bar, manually operable means for rotating the rear supporting wheel including pedals actuatable by an occupant of said seat, said means for supporting the rear end of the body including an annular flange upon the steering post, a forked bracket fixed to the rear end of the body and partially embracing the steering post and resting upon said annular shoulder, and a spring attached to the rear end of the body and to the upright tubular post for yieldingly maintaining the forked bracket in engagement with the steering post.

In testimony whereof I affix my signature.

STEVE RICKY
